TURBINE WHEEL

Adolph L. Berger, Dayton, Ohio

Application September 22, 1944, Serial No. 555,385

2 Claims. (Cl. 60—41)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to turbine wheels and more particularly to turbine wheels adapted to be operated by the exhaust gases from an internal combustion engine for the purpose of driving a supercharger or other auxiliary equipment.

Turbine wheels which are driven by hot exhaust gases are subject to high degrees of heat and consequent rapid deterioration. Accordingly, it is desirable to provide some cooling means to maintain the temperature of such wheels below that of the driving gases. It is, therefore, an object of my invention to provide a turbine wheel structure having provision for maintenance of flow of a cooling medium therethrough and it is a further object of my invention to construct a cooling means for a turbine wheel so that a flow of cool air or other gaseous medium is maintained through the interior thereof during operation without the necessity of providing an auxiliary pumping device. To obtain the above objects, I provide a turbine wheel having a substantially hollow interior wherein is supported a baffle plate spaced from the walls of the interior both laterally and peripherally. There is further provided ingress and egress means for a cooling medium on opposite sides of the baffle plate and comprising ports so arranged that the egress port area is disposed at a greater radial distance from the axis of the turbine wheel than the ingress port area, so that differential centrifugal forces are thus obtained on the quantities of cooling medium disposed on opposite sides of the baffle plate, whereby a continuous flow of cooling medium around the baffle plate is maintained in the interior of the turbine wheel.

For a more complete understanding of my invention, reference may be had to the appended drawing showing a turbine wheel comprising a body made of generally plate-shaped walls 1 and 2 and having a series of turbine blades 4 welded peripherally about the edges of the walls 1 and 2 by means of welded seams 5, and thereby inclosing a baffle plate 6 supported at its center by being welded at 7 to a hub 8 formed integrally at the center of the wall 2. The baffle plate 6 is spaced laterally and peripherally from the faces of walls 1 and 2 which form the interior of the turbine wheel, as shown. Hub member 8 has an axial ingress bore 10 therethrough in alignment with a bore 12 provided centrally about the baffle plate

6 and a flow diverting cone 14 is provided on member 1 having an axis co-axial with bores 10 and 12. A plurality of egress ports 16 are provided in wall 2 and disposed peripherally about

5 the hub 8. A tubular shaft 18 is secured as by welding or the like at 19 to the hub 8 with the interior of the shaft communicating with the ingress bore 10 and the turbine wheel is thus supported for rotation on the tubular shaft 18.

10 In operation, a source of gaseous cooling medium such as air is connected through tubular shaft 18 to the interior of the turbine wheel via bores 10 and 12 where it fills the space on one side of the baffle plate 6. When the turbine wheel

15 is rotating, frictional drag on the gaseous cooling means causes rotation thereof and the ensuing centrifugal force compels flow of the gas radially outward and around the periphery of baffle plate 6 and thence radially downward and through the egress ports 16 outwardly of the interior of the

20 turbine wheel at the other side of the baffle plate. In view of the location of the areas of the egress ports 16 at a further radial distance from the axis of the turbine wheel than any portion of 25 the cross sectional area of the bore 10, there will be a greater total centrifugal force acting on any radial column of transverse unit area of the cooling medium on the ingress side of baffle plate 6 than on the egress side thereof, whereby a continuous flow of cooling medium, as indicated by the arrows, will be maintained while the turbine wheel is rotating, without the necessity of providing auxiliary pumping means of any sort for flow maintenance.

30 35 If desired, radially disposed vanes may be used between the baffle plate 6 and the interior surfaces of the walls 1 and 2, for the purpose of reducing relative slippage of the gaseous medium in installations where any slippage apt to affect operation of the device is likely to occur.

Having thus described my invention, I claim:

1. In a turbine wheel having a wheel body comprised of a pair of walls forming a hollow interior therebetween, a baffle plate disposed axially of said wheel body and supported within said interior and laterally and peripherally spaced from said walls, an ingress channel for a cooling medium comprising an open ended tubular shaft disposed axially of said wheel body, one of said walls having an axial bore and being concentrically secured to said tubular shaft at the open end thereof, said baffle plate having an axial bore therein in communication with the interior of said tubular shaft through the axial bore in said wall whereby said cooling medium has access to

the interior of said wheel body at one side of said baffle plate, an egress means for said cooling medium comprising a plurality of radially arranged bores disposed through said wall facing the opposite side of said baffle plate and located radially beyond said tubular shaft and disposed parallel to the axis thereof and having direct communication with the exterior of said wall, the quantities of cooling medium retained in said wheel body on opposite of said baffle plate having unequal centrifugal forces acting thereon when said turbine wheel is rotating, whereby said cooling medium is compelled by said unequal centrifugal forces to flow in contiguity with said walls from

the interior of said tubular shaft through said baffle plate and radially outward relative thereto, and around the periphery and radially downward thereof, and through said egress bores outwardly of said wheel body interior.

2. In a turbine wheel as set forth in claim 1, including a flow diverting cone disposed axially of the bore in said baffle plate for diverting axial flow of said cooling medium radially outward of said baffle plate said flow diverting cone being formed on the other of said pair of walls and arranged to protrude into the bore of said baffle plate and being concentrically spaced therein.

ADOLPH L. BERGER.
